(57) **CLAIM**

I claim the ornamental design for a leaf and trash bagging tool, as shown and described.

DESCRIPTION

FIG. 1 is an isometric view of a leaf and trash bagging tool showing my new design;

FIG. 2 is a front elevational view of the leaf and trash bagging tool;

FIG. 3 is a rear elevational view of the leaf and trash bagging tool;

FIG. 4 is a top elevational view of the leaf and trash bagging tool, where a bottom elevational view is a mirror image of the top view; and,

FIG. 5 is a left side elevational view of the leaf and trash bagging tool, where a right side elevational view is a mirror image of the left side.
